UNITED STATES PATENT OFFICE

LAWRENCE KOLANO AND THOMAS PALKA, OF WYANDOTTE, MICHIGAN

WINDOW SCREEN

Application filed October 14, 1929. Serial No. 399,577.

The invention aims to provide a new and improved assemblage of parts whereby upon opening of one of the conventional slidable sashes of a window, a screen may be horizontally withdrawn from the wall at one side of the window and disposed across the frame, whereupon the open sash may be slid into contact with said screen, thereby providing an unusually desirable relation of parts in which 5 the screen is always accessible for use when desired, but may be quickly slid back into the wall when it is not required.

With the foregoing in view, the invention resides in the novel subject matter herein- 15 after described and claimed, description being accomplished by reference to the accompanying drawings.

Fig. 1 is an elevation partly broken away and in section showing the screen in position 20 beneath the lower sash.

Figs. 2 and 3 are vertical transverse sectional views on the correspondingly numbered lines of Fig. 1.

Fig. 4 is a view similar to Fig. 1 but illustrating the screen-guiding frame in section and showing the screen confined within the wall.

Fig. 5 is a horizontal sectional view on line 5—5 of Fig. 4.

Fig. 6 is a perspective view of the screen-guiding frame.

The drawings above briefly described illustrate one form of construction and while such construction will be herein rather specifically explained, it is to be understood that within the scope of the invention as claimed, variations may be made.

A wall W is shown embodying the conventional studs S to which the outer sheathing and the inner wall covering are secured in the usual way. Set in this wall is a window frame F of conventional construction, in which the usual upper and lower sashes U and L are slidably mounted.

At one or both of its ends as desired, one stile of the frame F is formed with a vertical slot 6, and one of the studs S is provided with a vertically elongated notch 7 which is aligned with said slot and opens through the inner edge of said stud. A screen-guiding

frame 8 is received at one end in the slot 6 and between its ends is received in the inner portion of the notch 7, said frame embodying parallel upper and lower guide bars 9 preferably of channel form as shown most 55 clearly in Figs. 3, 4 and 6. At their inner ends, the bars 9 are connected by two vertical plates 10, and an end bar 11 connects the outer ends of said bars 9, said bar 11 and said outer ends of the bars 9 being secured by 60 screws or the like 11^a to a block 11^b within the wall W, said block being secured by suitable means 11^c.

A filler block 12 occupies the outer portion of the notch 7 and is flush with the inner edge 65 of the notched stud S, said block being secured in place by toe-nailing as seen at 13 or in any other desired way. The notching of the one stud S to receive the screen-guiding frame, the positioning of said frame within the slot 70 6 and the notch 7, the fastening of the block 12 in the open side of said notch, and the securing at 11^a provide a construction well adapted for use when installing the improved screen in frame buildings which have 75 been completely constructed prior to such installation, but if desired, the screen-guiding means could of course be built into the wall at the time of constructing the latter.

A screen 14 of any desired construction 80 is slidably engaged with the bars 9. This screen is of such length that when it is slid into the wall pocket (provided by the above described construction) its outer end is readily accessible at the notches 10^a in the plates 85 10, upon opening of the sash U or L (according to the end of the window at which the screen is installed). The inner end of the screen 14 is provided with appropriate depressions or the like 16 permitting it to be 90 readily gripped with the fingers for withdrawal from the wall pocket. When the screen is in this pocket and the sash closed, it interferes in no manner with opening and closing of the window. When use of the 95 screen is desired, the sash is opened, the screen withdrawn and extended across the window frame, and the sash then closed against said screen.

It will be seen from the foregoing that sim- 100

ple, inexpensive and desirable provision has been made for carrying out the objects of the invention, and attention is again invited to the fact that within the scope of said invention as claimed, variations may be made.

5. We claim:—

1. In combination, a wall and a window frame, one stile of said frame having a vertical slot at one end normally closed by a vertical edge of a sash, said wall having a pocket communicating with said slot and adapted to receive a horizontally slideable screen, whereby upon opening of said sash the screen may be withdrawn from the pocket and extended across the window frame.
10. 2. In combination, a wall, a window frame, one stile of said frame having a vertical slot at one end normally closed by a vertical edge of a sash, and upper and lower horizontal screen-guiding bars secured within said wall and extending to the ends of said slot, whereby upon opening of said sash, a screen engaged with said bars may be withdrawn from the wall and extended across the window frame.
15. 3. In combination, a wall embodying studs, a window frame set in said wall, one stile of said frame being formed at one of its ends with a vertical slot normally closed by a sash, one of said studs being provided with a vertically elongated notch alined with said slot, upper and lower horizontal screen guiding bars secured at the upper and lower ends of said notch and slot respectively, and a filler block secured in said notch and disposed flush with an edge of said one stud, whereby upon opening of said sash, a screen engaged with said bars may be withdrawn from the wall and extended across the window frame.
20. 4. A structure as specified in claim 2; together with vertical end members secured to said bars and forming therewith a rigid frame.
25. 5. In combination, a wall embodying studs, a window frame set in said wall, one stile of said frame being formed at one of its ends with a vertical slot normally closed by a sash, one of said studs being provided with a vertically elongated notch alined with said slot, upper and lower horizontal screen guiding bars secured at the upper and lower ends of said notch and slot respectively, a filler block secured in said notch and disposed flush with an edge of said one stud, vertical end members secured to said bars and holding them in fixed relation, and a block to which the outermost end member is secured, said block being secured in the wall, whereby upon opening of said sash, a screen engaged with said bars may be withdrawn from the wall and extended across the window frame.

In testimony whereof we have hereunto affixed our signatures.

LAWRENCE KOLANO.
THOMAS PALKA.
